UNITED STATES PATENT OFFICE.

JOHN F. FOSS, OF LOWELL, MASSACHUSETTS.

FLIER FOR SPINNING-MACHINES.

SPECIFICATION forming part of Letters Patent No. 228,809, dated June 15, 1880,
Application filed December 8, 1879.

To all whom it may concern:

Be it known that I, JOHN F. FOSS, of the city of Lowell, county of Middlesex, and State of Massachusetts, have invented a new and useful Improvement in Fliers for Spinning Machines, of which the following is a specification.

The object of my improvement is to provide a spindle to run in the flier of a speeder which shall be shorter than those heretofore used; to combine with such a spindle a quill, which shall be rotated by the spindle, and upon which the bobbin is placed, and upon which it moves as the traverse of the machine raises and lowers it; to combine with the flier of a speeder a quill which, by sustaining and strengthening it longitudinally and perpendicularly, prevents its arms or side pieces from being sprung outward by their centrifugal force when the flier is in rotation; to combine with the flier of a speeder a quill extending from the top to the bottom of the flier on which the bobbin traverses, which can have its top swung out from under the flier to permit the bobbin carried upon it to be doffed.

The nature of the invention will fully appear from the subjoined description, when considered with reference to the accompanying drawings, forming part of this specification.

In the accompanying drawings, in which similar letters of reference indicate like parts, Figure 1 is an elevation, partly in section, of a spindle and flier embodying my invention. Fig. 2 is an enlarged elevation of a portion thereof in section, showing the construction of the end of the spindle and a section of the quill and follower. Fig. 3 is an enlarged view, partly in section, of the top of the quill, the hollow nose, and sliding bolt.

A is the spindle, driven in the usual manner by a gear-wheel working with the bevel-pinion a. C is the sleeve attached to the flier, and having upon its lower end the flier-pinion c, which is driven by the usual bevel-gear wheel of such machine.

Between the gear c and the flier the sleeve has upon it the journal c², which forms the lower bearing of the flier H, which is composed of the bottom b, top b', and sides or arms b².

The top b' has a hollow nose, d, extending upward upon it, which forms the upper bear-

ing of the flier and permits the drawing or roving to be carried in to the bottom on the line of the axis of rotation.

Below the upper bearing, and from the top b' of the flier, depends a hollow nose, d², carrying a sliding stud or bolt, g, which extends downward and is provided with a pin, g', which extends out through the slotted hole d⁴ made in the shell of the nose d². By means of this pin or lug the bolt may be raised so as to be retracted entirely within the nose d², which has its end on a plane at right angles to the axis of the rotation of the flier, and forms a bearing-surface or socket, d³, upon which the quill hereinafter mentioned rotates. Between this hollow nose and the bottom of the flier b is placed the quill or tube e, having its center upon the line of the axis of rotation of the flier H, and having bearings e² upon its ends, upon which, when in position, it is free to rotate.

The lower bearing is formed upon the end of the quill to fit a bearing or socket, d³, formed in the flier. The upper bearing is formed upon the end of the quill, and in its interior, near the end into which the cylindrical bolt g fits and slides when the quill is in place. By this arrangement the quill is retained accurately in place with its center upon the axial line, regardless of the spindle within it. Upon one side of this quill is formed a slot, f, extending from near its lower end to a point near its center. In the hollow nose d² is placed a bolt or sliding stud, g, which, being forced upward, permits the top of the quill e to be swung out from under the hollow nose d², and the bobbin B to be doffed or removed when full and an empty one substituted.

The bolt g may be made to project from the quill e into the nose d² and rotate with the quill instead of the flier without departing from the spirit of my invention.

Within the quill the spindle A rises and falls, as it has heretofore in the fliers of such machines; but its upper end is removed, so that when it is at the lowest part of the traverse it extends only into the quill to the lowest part of the slot, and its top is made somewhat smaller, flattened, and extended sidewise out through the slot in a toe or lug, a', and the bobbin rests upon the top of such flattened and extended part. To form this toe or lug

the spindle is drawn down into a neck somewhat smaller than the body of the spindle, and the lug formed upon such neck has its upper edge curved downward and backward until united by the neck to the spindle, and its under edge is curved from the neck upward and forward at sufficient distance from the upper edge to permit of the end of the spindle being introduced through the flier before its attachment to its sleeve and into the interior of the quill by first inserting the toe, holding the parts obliquely to one another, and, as the toe passes through the flier or into the slot in the tube, bringing them parallel. The lug will then extend out through the slot, and when the mechanism is in place the top end of the quill can be, as before described, swung out toward its slotted side from under the stud, against which its end bears, without disturbing its adjustment and without binding upon the spindle, as would be the case if the spindle continued its normal size to its end. Therefore when the spindle is at the lower part of the traverse the upper end of the quill can be swung out to permit of the doffing of the full bobbin and the substitution of an empty one without in any way disturbing the driving mechanism of the flier or spindle.

Within the quill *e* is placed the tube *h*, which loosely fits its interior and rests upon the top of the spindle, so that as the spindle descends within the quill the tube will follow it and prevent waste and dirt from falling into the interior of the quill through the slot above the spindle. As the spindle rises this tube, being no longer than the unslotted part of the quill, is lifted into such part and in no way interferes with the traverse of the spindle.

It will be observed that in place of the long spindle extending up through the bobbin and carrying its weight and that of the cop formed upon it, and bearing unsupported all their weight and tendency to vibration and gyration, I have substituted a shorter spindle, which bears only the weight, and is not affected by any tendency which the bobbin with its load may have to vibrate or gyrate when in rapid rotation; that I have substituted in place of a spindle bearing the load of the bobbin and its cop, and which carried the load with the rise of the traverse farther and farther from the bearing of the spindle, a quill on which the bobbin, being raised by the spindle and carried farther from one point of support, is taken toward another, and which therefore can never be as far removed from a point of support as in the old structure, and is always between two such points, and being upon such quill, the vibration of the spindle can have little or no effect upon it; that in place of a flier whose strength and stiffness is limited to that of its arms, which cannot practically be greatly increased in size because of their greater resistance to the air and the greater power required to drive them when so strengthened, and because, with each addition of metal to

strengthen the arms, the centrifugal force, which is the primary cause of weakness, is augmented instead of diminished, and which, having such limit, limits the speed with which the flier can be driven. I have substituted a flier which is strengthened without adding to the weight of its arms, and independent of the size of the arms, by having the material placed so near the axis of rotation as to be but little affected by centrifugal force acting upon its substance, and which, being so strengthened, can be driven much faster with but little addition to the power, one in which the arms can be made smaller in diameter without destructively weakening it, and one, therefore, capable of being run with less power; that I have produced a spindle in which the tendency to vibrate and gyrate is greatly reduced by reason of the better support which it receives, and by reason of its being shortened above its bolster-rail, as well as by the fact that all lateral or vibratory motion of the bobbin is kept from acting upon it; that I have arranged and supported the bobbin upon a quill so that the tendency to vibrate or gyrate on account of irregularities in its load is greatly diminished, and that therefore I have produced a flier for spinning roving which runs steadier, can be run much faster, and produces more and better roving in a given time than those heretofore in use.

What I claim as new and of my invention is—

1. In combination, the flier *H*, having the bearings *d*³, with the quill *e*, wholly within the flier, and provided with end bearings, *e*², substantially as described.

2. In combination, the flier *H*, provided with the bearing-surfaces or sockets *d*³, with the quill *e*, which is provided with an end and exterior bearing at its lower end and an end and interior bearing at its upper end, substantially as described.

3. In combination, the flier *H*, provided with the hollow nose *d*², containing bolt *g*, with the quill *e*, having the annular upper bearing, *e*², within which the bolt *g* slides, substantially as described.

4. In combination, the quill *e*, provided with end bearings *e*², and the flier *H*, provided with bearing-surfaces or sockets *d*³, and the retractile bolt *g*, which forms a stud upon which the quill revolves at its upper end, substantially as described.

5. In combination, the flier *H*, provided with upper and lower attached sleeve-bearings, with the quill *e* and the spindle *A*, the quill being driven by the spindle, whereby the bobbin may be doffed without disconnecting the mechanism for driving the quill, substantially as described.
